US0D1072808S

(12) **United States Design Patent** (10) **Patent No.:** **US D1,072,808 S**
(45) **Date of Patent:** **** Apr. 29, 2025**

(54) **DISPLAY DEVICE**

(71) Applicant: **Samsung Display Co., Ltd.**, Yongin-si (KR)

(72) Inventor: **Yun Joo Yim**, Yongin-si (KR)

(73) Assignee: **Samsung Display Co., Ltd.**, Yongin-si (KR)

(**) Term: **15 Years**

(21) Appl. No.: **29/866,087**

(22) Filed: **Aug. 26, 2022**

(30) **Foreign Application Priority Data**

Mar. 4, 2022 (KR) 30-2022-0008780

(51) **LOC (15) Cl.** **14-02**

(52) **U.S. Cl.**

USPC **D14/341**

(57) **CLAIM**

The ornamental design for a display device, as shown and described.

DESCRIPTION

FIG. 1 is a perspective view of a display device according to the present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In the drawings, the broken lines illustrate portions of the display device that form no part of the claimed design.

1 Claim, 7 Drawing Sheets
